SMOKE PREVENTER

George M. Phillips, Louisville, Ky., and William P. Rutherford, deceased, late of Louisville, Ky., by Susan B. Rutherford, administratrix, Louisville, Ky.

Application September 6, 1941, Serial No. 409,896

1 Claim. (Cl. 110—55)

The present invention relates to steam boilers, furnaces and the like and has among its objects and advantages the provision of an improved smoke preventer which operates in an efficient manner, is easily installed in conventional boiler and furnace devices, and in which the system operates noiselessly and automatically.

In the accompanying drawings:

Figure 1 is a front elevational view of a steam boiler illustrating the invention applied thereto;

Figure 2 is a perspective view of a valve operating line having a lost motion connection with a fire box door of the furnace;

Figure 3 is a top plan view of two steam jetting devices for delivering steam to the burning gases

nected a branch chain 50 connected at 52 with an air intake door 54 pivoted to the wall 14 at 56. Branch chain 50 passes over a swivel sheave 58 and is provided with a weight 60. A weight 62 is also attached to one end of the chain 40 beneath a time control device 42.

When either of the doors 12 is opened, a pull is exerted on the chain 40 which elevates the weight 62. At the same time, the arm 38 is pivoted for opening the butterfly valve 36 to admit steam to the branch pipe 24 and the heads 32 for admission into the combustion chambers through the medium of the jets 34. Thus such admission of steam prevents smoking of the fire while the fire box doors 12 are opened for furnace loading purposes. The time control device 42 retards downward movement of the weight 62 so as to gradually shut the butterfly valve 36 after the doors 12 have been closed. In opening either door 12, the weight 60 is rendered free to open the valve 54, which weight is sufficiently less than the weight 62 to permit the latter to lift the weight 62 gradually with the closing of the butterfly valve 36.

Referring to Figures 4 and 5, the time control device 42 comprises two spaced and parallel bars 64 and 66 held in spaced relationship by sleeves 68 mounted on bolts 70. A shaft 72 is rotatably journaled in the bars 64 and 66 and has a sprocket 74 fixedly keyed thereto, which sprocket is located outside the casing wall 76 which encloses the time control mechanism. Wall 16 is made secure between nuts 78 on the bolts 70, and the casing wall is secured to the wall 14, as at 80.

The chain 40 passes over the sprocket wheel 74 and about a reversing pulley 82 mounted on a shaft 84 secured to the wall 76. To the shaft 72 is fixedly connected a large gear 86 meshing with a small pinion 88 keyed to a shaft 90 rotatably journaled in the bars 64 and 66. A brake wheel 92 is keyed to the shaft 90 and is engaged by a brake shoe 94 carried by a bar 96 pivotally connected at its lower end with one spacing sleeve 68. An adjusting screw 98 is connected with the bar 96 at its upper end and is provided with an adjusting nut 100. Screw 98 extends loosely through one of the bolts 78 and the sleeve 68 mounted thereon, and the adjusting nut 100 engages that sleeve. Thus the brake shoe 94 may be adjusted for variable pressure with respect to the brake wheel 92. Accordingly, the descending movement of the weight 62 may be controlled for time through adjustment of the brake shoe 94 for variably retarding rotation

Figure 4 is a side elevational view of a time control; and

Figure 5 is an end view of the device of Figure 4.

In the embodiment selected for illustration, Figure 1 illustrates a steam boiler 10 provided with the usual fire box doors 12 pivotally connected with the boiler wall 14 through the medium of hinges 16. The usual ash pit doors 18 are also hingedly connected at 20 with the wall 14 but form no part of the present invention.

A steam supply pipe 22 connects with a cross branch pipe 24 through the medium of a T connection 26. In Figure 3, right angular pipe branches 28 are connected with the branch pipe through the medium of elbows 30 and to each branch pipe 28 is connected a hollow head 32, each provided with a plurality of steam jets 34. The branch pipes 28 lie in a horizontal plane and the heads 32 are positioned inside the combustion chambers. The jets 34 also lie in a horizontal plane and are arranged in diverging relationship on each head 32 so as to direct steam jets horizontally in different directions throughout the widths of the respective combustion chambers.

Interposed in the steam supply pipe 22 is a butterfly valve 36 controlled through the medium of an arm 38 attached to a chain 40 passing through a time control device 42 and connected with one of the doors 12 and with the other door 12 through the medium of a branch chain 44. The greater portion of the chain 40 extends horizontally across the outer face of the wall 14 and is passed around a swivel sheave 46, with the branch chain 44 passing about a swivel sheave 48. The swivel sheaves 46 and 48 are secured to the wall 14. To the chain 40 is con-

of the wheel 92 which operatively connects with the sprocket 74 through the medium of the pinion 88, the gear 86 and the shaft 72.

In the event that the butterfly valve 36 should fail to operate in the manner intended, a by-pass pipe 102 is connected into the steam supply pipe 22. Globe valves 104 are interposed in the steam supply pipe 22 between the T connections 106 to which the by-pass pipe 102 is connected. A globe valve 108 is also interposed in the by-pass pipe 102. Thus the globe valves 104 may be closed, in the event of damage to the butterfly valve 36 which permits the valve 108 to be manually manipulated for the admission of steam until such time as the valve 36 is in condition for automatic operation as an incident to opening of either or both of the fire box doors 12.

Figure 2 illustrates a bracket 110 secured to one of the fire box doors 12. This bracket is provided with an opening 112 of sufficiently large diameter to permit the chain 40 to slide freely therein. To the lower end of the chain 40 is connected a weight 114. This weight is positioned a short distance beneath the bracket 110 in the closed position of the furnace door, so that the chain 40 has a lost motion connection with the door. The lost motion connection permits the door to be swung some distance before the bracket engages the weight 114 to the end that proper movement may be imparted to the valve arm 38. The other furnace door connected with the branch chain 44 is also provided with a bracket 110, and a weight 114 is also connected with the branch chain. The combined load of the two weights 114 and the weight 60 is less than the weight 62 so that the latter may move the valve 36 to its closed position at a rate determined by the time control device. The valve 36 in its closed position limits further downward movement of the weight 62.

The present invention operates efficiently with respect to the delivery of steam to the combustion chambers, the steam jets being directed in a horizontal plane in such diverging relation-

ships as to effectively distribute the steam throughout the combustion chambers. Mere opening of either or both the fire box doors opens the butterfly valve 36 for admitting steam to the jets, and the time control device 42 retards closing of the valve 36 for the desirable length of time, which time period may be varied through mere adjustment of the nut 100. In addition, the system operates noiselessly.

Without further elaboration, the foregoing will so fully illustrate the invention, that others may, by applying current knowledge, readily adapt the same for use under various conditions of service.

15. What is claimed is:

In a furnace, steam jet means located in the combustion chamber of the furnace, a steam pipe for supplying steam to said jet means, a normally closed valve in said steam supply pipe 20 for controlling the admission of steam to said jet means, a time control device, a flexible pull line operatively connected with said time control device and having a weight attached thereto beneath said time control device, a bracket fixed 25 to each of the fire box doors of the furnace, said brackets having openings, one end of said pull line extending through the opening of one of said brackets and being provided with a weight located below the bracket, a branch pull line connected with said first pull line and extending through the opening of the other of said brackets and provided with a weight located below the bracket, said brackets establishing lost motion connections between said fire box doors 30 and said first and branch pull lines, and an operating connection between said first pull line and said valve to open the valve when either or both of the fire box doors are open, said time control device retarding movement of said 35 first pull line by said first weight after the closing of the fire box doors.
